Primary Examiner — Mark Goodwin(74) *Attorney, Agent, or Firm* — Pierce Atwood LLP; Kevin M. Farrell, Esq.; Katherine A. Wrobel, Esq.(57) **CLAIM**

The ornamental design for a mower blade, as shown and described.

DESCRIPTION

FIG. 1 is a top isometric view of a mower blade showing my new design;

FIG. 2 is an enlarged section view of the broken line circled portion of the mower blade thereof, the broken line forms no part of the claimed design;

FIG. 3 is a top plan view thereof;

FIG. 4 is a front elevation view thereof;

FIG. 5 is a rear elevation view thereof;

FIG. 6 is a right side elevation view thereof; and,

FIG. 7 is a left side elevation view thereof.
